(57) **CLAIM**

The ornamental design for a golf putter grip, as shown and described.

DESCRIPTION

FIG. 1 is a top perspective view of the golf putter grip of my new design;

FIG. 2 is a bottom perspective view thereof;

FIG. 3 is a front elevational view thereof; the undisclosed opposite side being identical;

FIG. 4 is a top plan view thereof; the undisclosed opposite side being identical;

FIG. 5 is a right side elevational view thereof;

FIG. 6 is a left side elevational view thereof; and,

FIG. 7 is a reduced scale perspective view showing attached to an unclaimed golf club.

The broken line showing of a club wedge is included for the purposes of illustrating environmental structures and forms no part of the claimed design.
